UNITED STATES PATENT OFFICE.

CHARLES A. ERICHSON, OF STAMFORD, CONNECTICUT, ASSIGNOR TO THE
YALE & TOWNE MANUFACTURING COMPANY, OF SAME PLACE.

DESIGN FOR A PADLOCK-CASE.

SPECIFICATION forming part of Design No. 26,462, dated December 29, 1896.

Application filed November 16, 1896. Serial No. 612,372. Term of patent 3½ years.

To all whom it may concern:

Be it known that I, CHARLES A. ERICHSON, a citizen of the United States, and a resident of Stamford, in the county of Fairfield and State of Connecticut, have invented and produced a new and original Design for a Padlock-Case, of which the following is a specification, reference being had to the accompanying drawing, forming a part thereof.

The drawing is a front elevation of a padlock-case, showing my design.

The leading feature of my design consists in the body, which has the shape, form, or

configuration of an ellipse flattened on its upper side, substantially as shown. 15

The padlock-case is of elliptical shape, having a flattened side and a shackle.

Having thus described my invention, the following is what I claim as new therein and desire to secure by design Letters Patent: 20

The design for a padlock-case substantially as herein shown and described.

CHAS. A. ERICHSON.
